UNITED STATES PATENT OFFICE.

BENJAMIN F. HARTWELL, OF WINCHESTER, MASSACHUSETTS.

BOOT AND SHOE AND PREPARED INSOLE THEREFOR.

Application filed February 24, 1925. Serial No. 11,121.

My present invention is a novel boot or shoe construction, incorporating my novel form of laminated insole.

The present invention is primarily directed to the improvement in the so-called McKay boots or shoes, wherein an insole, upper materials and outsole are united by through and through stitching. For this purpose my improved insole is devised, which will enable the resulting shoe structure to be substantially waterproof, and yet without the objections heretofore found in so-called waterproof footwear. Furthermore, the resulting boot or shoe structure embodying my present invention enables the shoe to be so constructed and arranged as to retain extreme flexibility along the forepart, or forepart and shank. This feature is an important object, particularly for McKay shoe construction, wherein the uniting of the insole and outsole by through and through stitching, necessarily renders the shoe structure stiff and non-flexible. My present improvement overcomes this objection, and enables a McKay type of shoe to be made of extreme flexibility and also of an economical, simple and efficient construction.

In carrying out my invention I utilize a novel form of laminated insole, wherein the insole structure retains the desirable features of a leather layer or surface in foot receiving position, in combination with a water resistant and moisture proof layer or face of the insole. In making this prepared insole, I am enabled to use an extremely thin and therefore flexible and economical leather layer for the foot contacting face, which also constitutes a stitch retaining member. For the waterproof layer or face, I preferably employ a sheet of open textile material, such as buckram, jute or the like. This open textile material insures flexibility and the same is treated with a rubberized solution or surface, which treatment affords water-proofing, fills the interstices of the openwork textile weave in buckram, jute and the like, without stiffening the same, and also permits an extremely thin, strong article which ideally combines with a thin leather layer into my complete laminated and yet flexible and stitch-retaining insole. Furthermore, the rubberized solution or treatment for the buckram, generally presents a slightly roughened surface, which is in direct contact through the greater part of its area, with the outsole, it being custom-

ary to make McKay shoes without filling between insole and outsole, and this roughened insole surface gives added resiliency, while preventing squeaking, the rubberized surface layer in contact with the leather outsole affording this desirable result. Thus I obtain an extremely strong, flexible, stitch-retaining insole member, which can be economically made, cut or died to form, and incorporated into McKay shoe construction. 60

I may, if desired, also coat the leather surface of the insole with felt, which adds the further feature of giving a desirable thickness to the complete insole and permits the through and through or McKay stitching to sink entirely within the thickness of the felt layer, preventing the objectionable feature of a ridge in the foot contacting surface of the insole. This felt surface, however, is optional, and when used may be secured in position by any suitable adhesive. 70

The novel combination of a thin layer of leather, which can be a leather skiving, or otherwise waste material, which, however, will be of ample strength to retain the stitching in a McKay shoe construction, and which will readily adhere to a rubberized buckram, united by any desirable adhesive, and which also will readily enable a felt layer to be 80 cemented or united to the other surface, is, I believe, a distinct novelty in this art, and I wish to claim the same herein broadly. 85

Referring to the drawings; illustrating a preferred embodiment of my invention, 90

Fig. 1 is a plan view of my laminated insole;

Fig. 2 is a similar plan view of the insole with the felt surface;

Fig. 3 is a cross-sectional view on the line 3—3 of the insole shown in Fig. 1;

Fig. 4 is a cross-sectional view on the line 4—4 of the insole shown in Fig. 2; and

Fig. 5 illustrates a fragmentary portion of a McKay boot or shoe construction, utilizing my improved insole construction. 100

As shown in the drawings, my laminated insole 1, may be and preferably is, made either in sheet layers, and died out therefrom, or is made of appropriately died or cut blanks, and these blanks then united by cement or other adhesive. As illustrated in Fig. 3, showing on an enlarged scale, the insole comprises a leather layer 2, and a loosely woven textile layer 3 to which is applied a rubberized or waterproofing solution 4. This layer 2 may be and preferably is, ex- 110

tremely thin, and therefore of much less expense for leather than would be an ordinary McKay insole for the same shoe. The loosely woven textile layers 3 with the rubber solution 4, constitute practically one layer, and are united and prepared before being cemented to the leather layer 2. The rubber or waterproof solution 4 will practically unite with and fill the interstices of the 10 loosely woven layer 3; giving a firm waterproof coating on the surface 5 next the outsole, 15, while the foot contacting surface 6 is of leather, preventing the rubberized solution from undesirable contact with the 15 foot of the wearer, and eliminating "sweating" or "drawing" of the same. I find that I can employ, very advantageously, for the layers 3 and 4, the material now used for automobile tops, tire, trunk and bag covers, 20 and the like, this being made of extremely flexible material and affording an inexhaustible and economical source of supply. This material is usually waved slightly or pebbled, or with a slightly corrugated rubberized surface as a finish, and I find that this is desirable in adding resiliency between insole and outsole, as well as preventing squeaking, although the contact of a rubberized surface with the leather outsole 15, will itself eliminate squeaking during walking. The leather layer 2 affording the desirable 25 features above noted, as well as giving stitch retaining means to the complete insole, and stiffness and body to the same, while the 30 rubberized buckram gives waterproofness and added thickness desired for a suitable McKay insole, afford an ideal combination for this purpose and both unite firmly to each other by any suitable adhesive.

40 In Fig. 4 I have illustrated a modified form of the invention, wherein the leather layer 2 is united to the rubberized layers 3 and 4 on one surface and on the opposite surface is secured by adhesive to a felt layer 45 8. The addition of this felt layer does not detract from the resiliency of my laminated insole, while it imparts to same slightly added thickness, and also gives the very desirable 50 feature of enabling the McKay stitching 10, uniting the laminated insole, the upper 12, and outsole 15, to sink within the depth of

the felt 8, and thus be concealed from contact with the foot of the wearer.

Thus as shown in Fig. 5, I provide an improved boot and shoe construction of the McKay type, wherein a laminated and waterproof insole of extremely economical and flexible materials, with stitch retaining layer, waterproofed layer, and if desired a cushioning layer 8, are united, giving greater flexibility than is secured by a leather insole of equal strength, with the added feature of moistureproofness. I am aware that laminated insoles of various kinds have been suggested heretofore, but so far as I am advised, such laminated insoles always resulted in a stiffer and less flexible article; were necessarily expensive, and could not be and were not used for giving flexibility to a McKay shoe, in combination with waterproofness, stitch retaining and economy of production. The rubberized surface and solution 4, is of sufficient depth and tenacity to close tightly about the stitching as same is applied, thus preventing moisture from following the stitching through. This is a feature which I believe has not before been contemplated, and gives great desirability to my combined shoe construction.

My present invention is further described and defined in the form of claims as follows:

1. A McKay insole, comprising a plurality of layers united by adhesives, an intermediate layer being of thin leather, a layer of fabric united with said leather on one surface, and a layer of felt on the opposite surface, together with a waterproof impregnating material carried by the fabric layer.

2. A McKay boot or shoe, comprising an insole, upper materials, and outsole, through and through stitching uniting the same, waterproofing on the lower surface of the insole about the stitching whereby moisture is prevented from following through the same, in combination with a cushioning layer on the upper surface of the insole, through which the McKay stitching will be drawn and concealed.

In testimony whereof, I have signed my name to this specification.

BENJAMIN F. HARTWELL.
